UNITED STATES PATENT OFFICE.

JOHN SQUIRES, OF DETROIT, MICHIGAN, ASSIGNOR TO SIGNAL MOTOR TRUCK COMPANY, OF DETROIT, MICHIGAN, A CORPORATION OF MAINE.

DESIGN FOR A RADIATOR-FENDER.

49,373.

Specification for Design.

Patented July 11, 1916.

Application filed March 18, 1916. Serial No. 85,222. Term of patent 7 years.

To all whom it may concern:

Be it known that I, JOHN SQUIRES, a citizen of the United States of America, residing at Detroit, in the county of Wayne and State of Michigan, have invented a certain new, original, and ornamental Design for a Radiator-Fender, of which the following is a specification, reference being had therein to the accompanying drawings, forming part thereof, in which—

Figure 1 is a front elevation of the radiator showing my new design, and Fig. 2 is a side elevation thereof.

I claim:

The ornamental design for a radiator fender, substantially as shown.

JOHN SQUIRES.

Witnesses:

JAMES P. BARRY,
ARTHUR D. PULVER.
